UNITED STATES PATENT OFFICE.

THOMAS R. EVANS, OF PHILADELPHIA, PENNSYLVANIA.

IMPROVEMENT IN OVER GAITER-SHOES.

Specification forming part of Letters Patent No. 131,862, dated October 1, 1872.

To all whom it may concern:

Be it known that I, THOMAS R. EVANS, of the city and county of Philadelphia, State of Pennsylvania, have invented an Improved Over Gaiter-Shoe, of which the following is a specification:

The object of my invention is to ventilate and to render more comfortable to the wearer the over gaiter-shoe for which Letters Patent No. 113,149 were granted to me on the 28th day of March, 1871; and I accomplish this object, first, by perforating that portion of the vamp or tongue A of the shoe which is concealed beneath the loose gaiter-flap B with a number of holes, a, as best observed in Figure 1; and, second, by securing a loose gaiter-flap to the rear portion of the body D of the shoe by rubber-cloth gussets E, as plainly shown in Fig. 2.

Air can gain access to the perforations a beneath the loose gaiter-flap, and can pass thence to the interior of the shoe for the purpose of ventilating the same; and the said perforations also render the vamp very pliable and self-accommodating to the instep.

By adopting the rubber-cloth gussets E for the gaiter-flap, the usual buttons or laces may be dispensed with, and the said flap is rendered self-accommodating with the perforated vamp to the shape of the instep and movements of the foot.

I claim as my invention—

1. The combination, substantially as described, of the perforated tongue or vamp A with the loose gaiter-flap B.
2. A loose gaiter-flap secured to the body of a shoe by rubber-cloth gussets E, substantially as and for the purpose described.

In testimony whereof I have signed my name to this specification in the presence of two subscribing witnesses.

THOS. R. EVANS.
